UNITED STATES PATENT OFFICE.

GEORGE N. HEIN, OF SAN FRANCISCO, CALIFORNIA.

NEEDLE-RETAINING DEVICE FOR SYRINGES.

Application filed August 26, 1924. Serial No. 734,209.

To all whom it may concern:

Be it known that I, GEORGE N. HEIN, a citizen of the United States, residing at the city and county of San Francisco, and State of California, have invented certain new and useful Improvements in Needle-Retaining Devices for Syringes, of which the following is a specification.

My invention relates in general to the class of hypodermic needle syringes, and in particular to a type of such syringes in which the syringe barrel is provided with a discharge nipple adapted for the frictional association therewith of a socket base 10 of a needle, or other member carrying said needle. My invention consists in the novel retaining assembly hereinafter fully described by reference to the accompanying drawings illustrating its best and preferred 15 form, it being understood that changes may be made within the scope of the claims hereunto appended without departing from the spirit of the invention.

In the drawings, Fig. 1 is a longitudinal 20 section of my retaining assembly showing the direct connection of a needle member with the syringe barrel.

Fig. 2 is a view enlarged, of the specialized retaining helix spring of said assembly.

Fig. 3 is a longitudinal section of the assembly showing the connection of a needle-carrying member with the syringe barrel.

1 is the barrel, and 2 is the piston of a syringe. The barrel 1 is provided with a 25 discharge nipple 1' for the needle or needle-carrying member connection. The nipple is substantially cylindrical in cross section and tapers exteriorly to its extremity. This syringe will be recognized by those familiar 30 with the art as a standard type, in which the tapered nipple is adapted for the ready detachable association and retention of the socket base of the needle or other member by frictional contact without the presence 35 of threads or other fastening feature.

I have found, however, that such frictional contact is often insufficient and I have, therefore, provided an independent retaining device of a character readily adapted 40 for this type of syringe without requiring any change in the original manufacture either of the syringe, nipple, or of the needle or needle-carrying member. This device 45 consists of the helical spring 3, having in its best and developed form specialized features, as shown in Fig. 2. It will be

noted that the helix is tapered; also that its coils between its terminals are of relatively large pitch with respect to its terminal coils 3' and 3"; and also that the 50 terminal coil 3' at the smaller end is of such relatively small pitch that it lies in close proximity to the adjacent coil and is in a plane approximately or substantially at right angles to the axis of the helix. It 55 follows that said smaller terminal coil 3' has relatively stronger resistance to expansion stress than its larger terminal coil 3". Therefore when the helix spring 3 is entered, small end first, upon the tapered barrel 60 nipple 1' the smaller terminal coil 3', pressed tightly home, will bind upon or grip the relatively large base of the nipple with sufficient accuracy and stability, both by reason of its substantially right angular 65 position and its increased resilient strength, to effectively retain the helix upon the nipple for all practicable purposes.

Referring now particularly to Fig. 1, 4 is the needle having the usual socket base 4' 80 with the terminal exterior peripheral bead 4". When the socket base of the needle is entered upon the barrel nipple 1', the bead 4" of said base passes within helix spring 3, the larger terminal coil 3" of the spring 85 slipping readily over the bead 4" of the needle base 4' and snapping down behind said bead with holding effect. In this fitting of the needle to the helix-armed nipple, it will be seen that the operation is 90 one which is readily and easily performed due to the spacious outer end of the helix, and the relatively large resilient nature of said end, and also that the retention of the needle while sufficient for operative purposes is yet capable of being easily broken 95 in order to remove the needle, without disengaging the helix from the nipple.

In cases where, between the syringe and the needle proper it is necessary to use some 100 form of needle-carrying extension or member, such member will have a socket base similar to the base of the needle, while its other end may be provided with any suitable retaining device for the needle proper. 105 This I show in Fig. 3 wherein one form of extension member is indicated by 5 having at one end a socket base 5' with exterior bead 5", said base being fitted to the helix-armed nipple of the syringe barrel as heretofore described with reference to the direct attachment of the needle proper. The other 110

end of the extension member 5 may be provided with a similar helix attachment, but for the purposes of illustration I have shown a needle fastening comprising a 5 nipple 6 of said extension member adapted to receive the socket base of the needle, and a U-shaped spring 6' received between collars 6" on the extension member, the arms of said spring being adapted to resiliently 10 bear upon the needle base.

I claim:

1. A needle retaining assembly for syringes comprising a syringe barrel having a discharge nipple; a helical spring resiliently engaging at its inner end the base of said nipple the remainder of said spring surrounding and spaced from said nipple; and a member having a socket base fitted upon said nipple and within said spring, 15 the outer end of the spring resiliently engaging said base.

2. A needle retaining assembly for syringes comprising a syringe barrel having a discharge nipple; a helical spring fitted 20 upon said nipple, said spring being tapered

and its coils decreasing in pitch from its outer to its inner end, the inner terminal coil resiliently engaging the nipple and its remaining coils spaced therefrom; and a member having a socket-base fitted upon 25 said nipple and within said spring, the outer terminal coil of the spring resiliently engaging said base.

3. A needle retaining assembly for syringes comprising a syringe barrel having 30 a forwardly tapering discharge nipple, a helical spring fitted upon said nipple, said spring being tapered and its coils decreasing in pitch from its outer to its inner end, the inner terminal coil resiliently engaging the 35 enlarged base of the nipple, and its remaining coils spaced from the nipple; and a member having a socket base fitted upon said nipple and within said spring, said base having an exterior bead, with which the 40 outer terminal coil of the spring resiliently engages.

In testimony whereof I have signed my name to this specification.

GEORGE N. HEIN.
